U.S. Appl. No. 29/372,405, Applicant: Bo-Ra Kim et al., filed Nov. 16, 2010 entitled MP3 Player.

(Continued)

Primary Examiner — Prabhakar Deshmukh(74) *Attorney, Agent, or Firm* — Flynn, Thiel, Boutell & Tanis, P.C.(57) **CLAIM**

The ornamental design for a MP3 player, as shown and described.

DESCRIPTION

FIG. 1 is a top front perspective view of a MP3 player showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
